UNITED STATES PATENT OFFICE.

CHARLES CLAYPOOL, OF SPENCER, IOWA.

WINDMILL.

SPECIFICATION forming part of Letters Patent No. 415,811, dated November 26, 1889.

Application filed July 10, 1889. Serial No. 317,047. (No model.)

To all whom it may concern:

Be it known that I, CHARLES CLAYPOOL, a citizen of the United States of America, residing at Spencer, in the county of Clay and 5 State of Iowa, have invented certain new and useful Improvements in Windmills, of which the following is a specification, reference being had therein to the accompanying drawings.

10 My invention relates to machines designed to overcome the dead-centers in wind-pumps or other mechanisms operated by wind-wheels; and it consists in certain improvements in construction, hereinafter described 15 and claimed.

In the accompanying drawings, Figure 1 is a front view of the machine; Fig. 2, a sectional view showing the pawl-and-ratchet mechanism and device for throwing the machine out of gear, and Fig. 3 an end view of the parts shown in Fig. 2.

Similar letters refer to similar parts throughout the several views.

A represents a spur-wheel the rim of which 25 is attached or cast to the sides of the spokes and its inner circumference ratcheted, as shown in Fig. 1. Meshing with the spur-wheel is a pinion B, mounted upon the shaft b, which revolves in bearings in the supporting-frame C. Mounted upon the shaft b is a pulley D, connected by a belt E with a smaller pulley F, mounted upon the shaft f. Upon the outer end of the shaft b is mounted a fly-wheel G. The shaft f is also adapted at its 30 outer end to fit the fly-wheel G, so that the latter may be mounted upon either shaft, according to the velocity of the windmill, thus securing at all times a steady and uniform motion of the machine. Upon the shaft of 35 the spur-wheel A are loosely mounted the two arms H H', each of which has at its outer end a guide I, consisting of two pieces with projecting flanges adapted to inclose the ratchet-teeth upon the inner circumference 40 of the spur-wheel and hold the pawl J in position, the latter being pivoted between the two sections of the guide, as shown in Fig. 3. Each of the pawls J J' is attached to its pivot-pin, which passes through and projects beyond the face of the guide. Upon one end of 45 the pivot-pin is loosely mounted the bent arm M, having at its outer end a weighted ball, and upon the pivot-pin-outside of the arm M is a shoulder N, with two projecting arms n n', adapted to engage with the outer end of 50 the bent arm M. It will be seen that when the weighted arm M, rest against the arms n the pawls will be held against the ratchet-teeth; but if the arms M are turned so as to 55 rest against the arms n' the pawls will be disengaged and the machine thrown out of gear. The arms H H' are pivoted to the connecting-rods K K', one of which is pivoted to the reciprocating shaft L above the spur-wheel and the other pivoted to the reciprocating shaft 60 below the spur-wheel at such position as to bring the guides I I' to the upper part of the spur-wheel and about one-fourth of its circumference distant from each other when the reciprocating shaft is at the upper end of its 65 stroke. As the reciprocating shaft L makes its downward stroke it carries the connecting-rods K K' down, and the pawl J' will engage 70 the ratchet-teeth and cause the spur-wheel to revolve, while the other pawl J will pass over 75 the ratchet-teeth without engaging them; so that when the reciprocating shaft reaches the end of the stroke the guides I I' will be at the lower side of the spur-wheel. As the reciprocating shaft makes its upward stroke, carrying the rods K K' upward, the pawl J will engage 80 the ratchet-teeth and complete the revolution of the spur-wheel, while the other pawl J' will pass over the ratchet-teeth until the upper end of the stroke is reached. In this 85 way the perpendicular motion of the reciprocating shaft is converted into circular motion, the spur-wheel revolving continually from right to left. The rate of speed imparted to the spur-wheel by a stroke of the reciprocating shaft depends upon the length of the arc 90 traversed by the pawl, and if the connecting-rods are pivoted to the arms H H' near the shaft of the spur-wheel the speed of the latter will be greater than where the rods are 95 pivoted to the outer ends of the arms.

I am aware of the United States Patent No. 192,623 to C. Hammelmann, and I do not claim as my invention anything shown or claimed in said patent; but

100 What I claim, and desire to secure by Letters Patent, is—

The combination, with the spur-wheel A, having ratchet-teeth upon its inner periphery, the arms H H', pivoted upon the shaft of the spur-wheel and provided at their outer ends 5 with the flanged plates I I', and the connecting-rods K K', pivoted to the arms H H' and to the reciprocating shaft L, of the pawls J J', pivoted between the plates I I', each of said pawls being attached to its pivot-pin, one end of which projects through the plate and

is provided with a shoulder N, and the bent arms M M, weighted at their outer ends and loosely mounted upon said pivot-pins, as and for the purposes specified.

In testimony whereof I affix my signature in 15 presence of two witnesses.

CHARLES CLAYPOOL.
